UNITED STATES PATENT OFFICE.

WILLIAM E. WINE, OF TOLEDO, OHIO.

CAR-DOOR CONSTRUCTION.

Application filed January 22, 1923. Serial No. 614,189.

To all whom it may concern:

Be it known that I, WILLIAM E. WINE, a citizen of the United States, residing at Toledo, in the county of Lucas and State of Ohio, have invented certain new and useful Improvements in Car-Door Constructions; and I do hereby declare the following to be a full, clear, and exact description of the invention, such as will enable others skilled 10 in the art to which it appertains to make and use the same.

This invention relates to car construction with particular reference to hopper car doors and securing means therefor. Among 15 the objects is to provide improvements in car door supporting mechanisms and improvements in the construction of the car in the vicinity of the doors. Another more specific object is to provide in combination 20 with a car door having an inclined hopper sheet, a spacing member set out from the hopper sheet and from the door upon which the door securing mechanism may be located.

With such objects and others in view, the 25 invention consists of the formation, combination and arrangement of parts as will be herein described and particularly claimed.

In the accompanying drawings which show a preferred form of the invention:

30 Figure 1 is a fragmentary side elevational view of a portion of a hopper car and the door arrangement thereof, the same being constructed in accordance with the principles of the present invention.

35 Figure 2 is an end elevational view of the hopper showing also the door supporting mechanism, this figure being seen from the direction of the arrow 2 in Figure 1.

The car shown in the drawings is of the 40 side dump type, although the invention is applicable to many other types of cars, as for example, the twin hopper type and any other type wherein inclined hopper sheets are employed. In the drawings the numeral 45 1 indicates the side of the car to which is hinged an outwardly swinging side dump door 2 by means of hinges 3. An inclined hopper sheet is shown at 4, and at 5 is shown a vertically arranged end hopper sheet which may be attached to the foot of the inclined hopper sheet as by means of rivets 6. A transversely inclined chute plate is shown at 7. The door 2 is arranged 50 to close along the outer edge 8 of the chute plate and the outer edge of the sheet 5, and may extend also further up along the edge 55

of the side plate 1. The outer edge of the sheet 5 may be flanged as at 22 to form a flat bearing face for the door. The adjacent edge of the door may also be provided 60 with a vertically arranged stiffening member 23 and a horizontal stiffening member 24 may extend along the upper outer face of the door. The lower edge of the chute plate 65 may also be supplied with the longitudinal stiffening beam 25.

A main stiffening member 9 extends lengthwise of the door and is riveted thereto by means of rivets 10. This stiffener is shown in the drawings as formed of a 70 structural Z-bar. Attached to the outer end of this Z-bar is an angle iron extension 11, which is secured to the Z-bar by means of rivets 12. This angle iron extends outwardly beyond the end of the hopper discharge opening and beyond the outer face of the hopper end sheet 5, and is arranged for cooperation with a door supporting hook or lever 13. The angle iron is notched 75 at 27 where the lever 13 engages with it. 80 The Z-bar 9 is itself shown in the drawings as extending slightly beyond the plane of the hopper end sheet 5, but this is immaterial so long as a suitable door arm is arranged to extend outwardly from the end 85 of the door.

The hook arrangement is of the well known type such as is shown in the Wine Patent No. 1,431,506, issued October 10, 90 1922, and the detail construction of the hook, the cam and the bracket will therefore not be described.

In many cars where it is desired to use this type of door-securing hook, the stiffening member, such as the Z-bar 9, is located 95 close to the intersection 14 of the plane of the end sheet 5 and that of the inclined hopper sheet 4. This makes it impossible to apply such hook devices directly to the end sheets of the hoppers without incurring the 100 labor and expense of cutting off the stiffening members and lowering them on the doors. Furthermore, it frequently happens that some limitation of the car construction or the road clearance will prohibit the necessary lowering of this stiffening member, and it is difficult to make a proper application 105 of the device to such cars. It also frequently happens that the end hopper sheet 5 is of too small extent or is incorrectly located to permit of the direct application thereto of the hook mechanism, and the 110

plane of the sheet 4 is often too flat to permit of placing the hook upon a parallel plane for direct cooperation with the horizontal door arm.

6 The present invention provides a suitable means whereby this type of door supporting mechanism may be applied to any of such cars without the removal of the stiffening members, and furthermore locates the supporting lever at a more accessible point. In order to effect this, a separate bracket 15 is applied to carry the locking mechanism. This bracket is riveted to at least one, and preferably, as shown in the drawings, to 10 both of the sheets 4 and 5. When so attached to both of them, as by means of the rivets 16 and 17, respectively, it constitutes a brace between these parts and better stiffens the two parts and also effectively holds 15 the door locking mechanism in correct relationship with the door. The main portion 18 of this bracket is set at an angle with the line of the door arm 11 and the hook outfit lies in a plane parallel with and against the 20 exposed face of this portion of the bracket. This causes the hook to engage the door arm 11 at an acute angle, which is an advantage in assisting to force the door shut and to prevent the hook from creeping off the end 25 of the angle.

The bracket 15 is preferably formed of a bent plate having a portion 19 lying directly against the outer face of the end sheet 5, and a portion 20 outstanding substantially at right angles thereto. The inclined portion 18 extends on an angular line from the outer end of the outstanding portion 20 to the inclined plane of the sheet 4 where the upper end 21 of this bracket is 30 again bent to agree with the sloping plane of the plate 4. The portion 18 of the bracket is disposed in an intermediate plane to cause the hook to cooperate suitably with the door arm and also to provide the necessary space for the reception of the lock 35 mechanism. The bracket is also so formed as to require the least practical projection of the door arm beyond the edge of the door. Liners or washers such as 26 may be employed on the inner faces of the plates 4 and 5 where the rivets 17 and 21 pass through these sheets for the attachment of the bracket 15. This has been found desirable where new material, such as this 40 bracket, is applied to cars whose plates have become thin from severe corrosion.

This makes a form of bracket that can be readily produced in simple bending dies at a single blow and without excessive manufacturing costs. I have thus described a 45 preferred embodiment of my invention.

Other embodiments are contemplated within the scope of the patent claims without departing from the spirit thereof.

What is claimed is:

1. A railway car having an inclined hopper sheet and a vertical hopper sheet extending downwardly from the foot thereof, a bracket lying in the exterior angle formed by said sheets and connected to at least one 70 thereof, a door arranged to lie, when closed, with one edge near the said bracket, and door-supporting means operatively interposed between and cooperating with the said door and the bracket.

2. A railway car having an inclined hopper sheet and a vertical hopper sheet extending downwardly from the foot thereof, a bracket lying beneath the inclined sheet and having a portion arranged upon a plane of inclination greater than that of the said inclined hopper sheet, said bracket being connected to at least one of said sheets, a door arranged to lie, when closed, with an edge near said bracket, and door-supporting 80 means carried by the bracket.

3. A railway car having an inclined hopper sheet and a vertical hopper sheet extending downwardly from the foot thereof, a bracket extending between and connected to said sheets, a door arranged to lie, when closed, with one edge near the said bracket, an arm secured to and extending outwardly from the door, and an arm-engaging hook pivoted upon the bracket and adapted to 90 support the door in closed position.

4. A railway car having an inclined hopper sheet, a door arranged to swing transversely of said sheet and to lie when closed with one edge thereof near the foot of said inclined sheet, a door-supporting arm extending outwardly from the door near the foot of the said inclined sheet, a bracket disposed beneath the inclined sheet and secured thereto, and a lever carried by the bracket 100 and adapted to supportingly engage the said arm.

5. A railway car having an inclined hopper sheet and a door adapted to swing at right angles thereto, said door, having one edge thereof arranged to lie, when in closed position, adjacent the said sheet and having an arm projecting outwardly beyond the edge of the door and below the said inclined hopper sheet, a bracket connected to the 110 said hopper sheet, and a door-supporting hook pivoted upon the bracket, the same being arranged for cooperation with the said arm.

In testimony whereof I affix my signature.

WILLIAM E. WINE.
